ATTORNEY.

UNITED STATES PATENT OFFICE.

GEORGE EDWARD WALDECK, OF JERSEY CITY, NEW JERSEY.

DESIGN FOR A BOX-BODY.

SPECIFICATION forming part of Design No. 29,645, dated November 8, 1898.

Application filed October 6, 1898. Serial No. 692,854. Term of patent 7 years.

To all whom it may concern:

Be it known that I, GEORGE EDWARD WALDECK, a citizen of the United States, residing at Jersey City, in the county of Hudson and State of New Jersey, have invented and produced a new and original Design for a Box-Body, of which the following is a specification, reference being had to the accompanying drawings, forming part thereof, and in which—

Figure 1 is a perspective view of a box-body incorporating my design, and Fig. 2 is a top view of same.

In the drawings, A designates the main body of the box, and B the bottom thereof. The body A is of rectangular outline and has at its vertical corners the angular sections

C, which impart to the said body a polygonal outline in horizontal cross-section.

The bottom B extends upward a short distance around the sides of the body A and conforms to the general polygonal outline thereof, as shown.

What I claim is—

The design for a box-body, substantially as shown and described.

Signed at Jersey City, in the county of Hudson and State of New Jersey, this 8d day of October, 1898.

GEORGE EDWARD WALDECK.

Witnesses:

JOHN TROSSEBACH,

JAMES KIERNAN.
